UNITED STATES PATENT OFFICE

2,417,087

LUBRICANT

Carl F. Prutton, Cleveland, Ohio, assignor to The Lubri-Zol Corporation, Wickliffe, Ohio, a corporation of Ohio

No Drawing. Application December 19, 1940,
Serial No. 370,839

10 Claims. (Cl. 252—42.7)

1

This application is a continuation-in-part of my co-pending application, Ser. No. 216,153, filed June 27, 1938, which in turn was a continuation-in-part of my co-pending application, Ser. No. 760,038, filed December 31, 1934, now Patent No. 2,121,825, which was in turn a continuation in part of co-pending applications Serial Nos. 635,701; 635,599 and 679,594, now respectively Patent Numbers 1,986,651; 1,986,645 and 2,051,744; also application Ser. No. 737,070, filed July 26, 1934, and application Ser. No. 158,531, filed August 11, 1937, now Patent No. 2,121,824.

The above identified applications disclose the use, in the field of lubrication, of halogenated carbon ring compounds. Said applications more specifically disclose the fact that certain of the above-named type of compounds, when added in very small amounts to a lubricating oil such as a mineral oil, impart "extreme pressure" characteristics thereto, i. e., a lubricating film formed of such material, when occurring between relatively moving metallic bearing surfaces is capable of withstanding considerably greater pressures per unit area, before such film is ruptured, than previously known lubricants, particularly mineral oil when used in its pure state.

This invention relates to the discovery that certain compounds, among which are included certain compounds covered by the broad class, as defined in my above identified applications, are likewise particularly useful in the field of lubrication.

Certain of the compounds to which the present invention relates are particularly useful as means for imparting extreme pressure characteristics to lubricating compositions generally, such as lubricating oils; as means to impart certain characteristics to lubricating compositions not ordinarily possessed thereby and also to function as primary lubricants either in their pure state or combined with other lubricating constituents.

It is a principal object of my invention, therefore, to provide, for use in the field of lubrication, certain materials having a wide variety of usage and by the use of which certain results may be obtained which have heretofore been impossible.

Other objects of my invention will appear as the description proceeds.

To the accomplishment of the foregoing and related ends, said invention, then, consists of the features hereinafter fully described, and particularly pointed out in the claims, the following description setting forth in detail certain embodiments of the invention, these being illustrative, however, of but a few of the various ways in

2

which the principle of the invention may be employed.

Broadly stated, this invention contemplates the use in the lubricating field of such materials as may properly be defined as substituted organic ring compounds containing an aliphatic substituent and an element in addition to carbon and hydrogen.

The element in addition to carbon and hydrogen above referred to will advantageously be an element other than oxygen, and for certain uses an element other than oxygen or nitrogen. This additional element may be present with either oxygen or nitrogen, and for certain uses preferably with oxygen.

From the foregoing statement defining broadly the addition agents contemplated for use in the present invention, it will be observed that the molecule of such addition agents contains:

- 20 (a) An aromatic nucleus;
- (b) An aliphatic substituent; and
- (c) Another element.

25 This other element (c) is preferably in the form of an inorganic substituent, which also contains oxygen or sulphur.

By inorganic substituents as used herein, I mean to include all substituents which either 30 consist of or contain one or more of the following elements:

The halogens, e. g.,

Chlorine

Bromine

Fluorine

Iodine

Sulphur

Phosphorus

Arsenic

Nitrogen

The metals

When sulphur is present as part of a substituent group, it may, for example, be present in any 45 of the following:

- (1) Mercapto $(-SH)$
- (2) Sulphide $(-S-R)$

where the radicle is directly attached to a C atom.

- (3) Polysulphide $(-S_x-R)$

where x equals at least 2.

- (4) Thio-cyanate $(-SCN)$

55

(5) Thio-ketone

(6) Thio-aldehyde

(7) Thio-carboxyl

and

(8) Thio-ester

and

When the inorganic substituent also contains oxygen in addition to the characterizing inorganic element, such substituent may be any of the following, for example:

- (1) $(-\text{O}-\text{M}$ where M is a metal)
- (2) Amide and substituted amide

- (3) Where the oxygen is directly attached to a carbon atom: arsenite, hypochlorite, phosphite, thiophosphate, thiophosphite, and β hydroxylamines.
- (4) Where the oxygen is indirectly attached through the means of some other atom, e. g.: arsenate, chlorate, chlorite, cyanate, α hydroxylamine, nitrate, nitrite, nitro, nitroso, oxime, perchlorate, phosphate, sulphate, sulphite, sulphuric acid, sulphone, sulphonic acid, sulphoxide, and thiosulphate.

Additional examples of inorganic substituents are those thio substituents which correspond to the oxygen containing substituents given immediately above under (1), (2), (3) and (4), but in which one or more of the oxygen atoms in any of the substituents of (1), (2), (3) and (4) above are replaced with sulphur, for example,

Mercaptide ($-\text{S}-\text{M}$)
Thioamide, etc.

The following are specific examples of metals which may be included in the foregoing list comprising the inorganic substituent:

Sodium	Manganese
Potassium	Aluminum
Ammonium	Chromium
Lithium	Tin
Magnesium	Lead
Calcium	Copper
Strontium	Cadmium
Barium	Bismuth
Cobalt	Silver
Zinc	Mercury
Nickel	Vanadium

From the foregoing, it will be observed that component C, i. e. the third component of the molecule of the addition agents of the present invention, is preferably an inorganic radicle which contains oxygen or sulphur, and in addition preferably contains a metal.

The oxygen or sulphur acts as a means of attaching the addition agent to metallic surfaces so that it will be most effective for the protection of such surfaces, especially under conditions of

boundary or thin film lubrication. Conditions which produce boundary or thin film lubrication are those in which the bearing surfaces are not completely separated by a fluid film. This may result from high unit loading, e. g. in excess of ten thousand pounds per square inch; low speeds; high temperatures; or a deficiency of lubricant.

This invention also contemplates the use in the field of lubrication of compounds which may be defined as products of reactions taking place in the presence of certain catalysts, such as anhydrous aluminum chloride, between certain unsaturated organic compounds and organic ring compounds.

15 By reference to certain of my above-identified co-pending applications and the applications with which they were related by co-pendency, certain groups of compounds will be found which come within the scope of the present invention, namely, 20 the halogenated, or more specifically, chlorinated homologs, (i. e., compounds carrying alkyl side-chains) of benzene, naphthalene, and diphenyl. Examples of these compounds will be found to include halogenated, or more specifically, chlorinated, toluene, methyl naphthalene, phenyl toluene, and xylene.

With reference to the compounds which may be prepared by the reaction between certain unsaturated organic compounds and organic ring 30 compounds in the presence of catalysts such as anhydrous aluminum chloride, the following is an outline of the procedure which may be followed and the materials which may be employed in such procedure.

35

CATALYSTS

The catalysts, which it is possible to employ in carrying out the condensation reaction to form certain of the products contemplated for use in 40 the lubrication field by this invention, may be broadly defined as any catalysts which promote condensation reactions of the above type; specific examples of such catalysts are anhydrous aluminum chloride, anhydrous ferric chloride, and 45 the addition products formed in the reaction of such anhydrous chlorides with olefines such as ethylene; for example, the addition product of anhydrous aluminum chloride and ethylene, $\text{AlCl}_3 \cdot \text{C}_2\text{H}_4$. Generally speaking, the broad class 50 of catalysts capable of being used are those well known in the art as being substantially the equivalent of anhydrous aluminum chloride.

UNSATURATED ORGANIC COMPOUNDS

55 The unsaturated organic compounds forming one component of the condensation reaction may be conveniently defined as compounds containing at least one pair of multiple-bonded carbon atoms, such as the groups $-\text{CH}=\text{CH}-$ and $-\text{C}\equiv\text{C}-$. This class of compounds includes those 60 which may be described as members of the olefine and acetylene series together with derivatives of them formed by substitution.

When the reaction components are an unsaturated organic compound of the olefine type and a ring compound of the aromatic type, the resultant product is probably in the nature of a homolog of the aromatic compound, e. g., an alkylated aromatic compound, and the reaction 65 may be expressed as follows:

where R' and R'' are organic radicles or hydrogens and R is an aromatic radicle.

The di-olefines or other poly-olefines such as those produced by polymerization of the olefines, (e. g. butylenes, pentenes, hexenes, etc.) produce similar products of a more complex nature and for certain purposes are of a preferred type. 5 Certain other unsaturated organic compounds are capable of producing products of the type contemplated. A preferred type of unsaturated compound is one containing one or more long chain structures such as the normal alkyl groups which contain more than three carbon atoms and preferably more than ten; for example, the lauryl, cetyl, ceryl, and melissyl groups. When such "long chain" unsaturated organic compounds are used, or when the unsaturated organic compounds are contained in a complex mixture, it may be desirable to use $AlCl_3C_2H_4$ as the catalyst rather than $AlCl_3$.

A complex mixture of unsaturated compounds is often preferred to a single pure compound, 20 and a preferred source of such compounds is found in the products of the so-called "cracking" process as applied to petroleum products; for example, cracked gasoline, cracked kerosene, cracked paraffin or other waxes, cracked heavy 25 oils, etc.

Unsaturated organic compounds other than hydrocarbons may also be used and may, for some purposes, give improved results. Included among such unsaturated compounds are the following classes:

Table No. 1

- (A) Oxygen-bearing substitution products (for further classification and examples see Tables Nos. 2 and 3 below). 35
 (B) Halogen-bearing substitution products.
 (C) Other substitution products such as those containing the following substituent groups:
 Amino, and substituted amino groups
 Imino
 Azo
 Hydroazo
 Hydrazine
 Nitrile
 Isonitrile
 Mercapto
 Sulphide
 Polysulphide
 Thiocyanate
 Isothiocyanate
 Dithiocarboxylic acids (also ester and salt groups derived therefrom). 45

NOTE: This invention contemplates the use of compounds containing more than one substituent group. In such cases the compound may belong in two or more of the above classes.

Examples of the oxygen-bearing compounds 50 are as follows:

Table No. 2

- (1) Unsaturated alcohols, e. g.,
 Vinyl ethyl alcohol
 Allyl alcohol
 Crotonyl alcohol
 Oleyl alcohol
 Propargyl alcohol 55
 (2) Unsaturated aldehydes, e. g.,
 Acrolein
 Crotonaldehyde
 Hexadienal
 Octatrienal
 Citral
 Propargylic aldehyde
 (3) Unsaturated ketones, e. g.,
 Allyl acetone
 Di-allyl ketone
 Mesityl oxide
 Phorone
 Vinyl lauryl ketone
 Acetylenic ketones (e. g. $R-C\equiv C-CO-R'$), such as:
 Allylene methyl ketone
 Allylene lauryl ketone
 (3a) Ketenes
 Ketene
 Acetylene ketone
 (4) Unsaturated ethers, e. g.,
 Di-vinyl ether
 Di-allyl ether
 Allyl ethyl ether
 Vinyl ethyl ether
 Allyl iso-amyl ether
 Allyl lauryl ether
 Propargyl ethyl ether 70
 75

(5) Unsaturated acids, e. g.,

- Vinyl acetic acid
 Vinyl acrylic acid
 Vinyl glycolic acid
 Acrylic acid
 Crotonic acid
 Oleic acid
 Linoleic acid
 Maleic acid
 Hydroxymaleic acid
 Fumaric acid
 Glutaconic acid
 Linolenic acid
 Elaeostearic acid
 Propiolic acid
 Stearolic acid
 Acetylene dicarboxylic acid

(6) Unsaturated anhydrides:

- Maleic anhydride
 Itaconic anhydride
 Citraconic anhydride
 Pyrochrochomic anhydride
 Xeronic anhydride
 Glutaconic anhydride
 Methyl glutaconic anhydride
 Dimethyl anhydride

(7) Unsaturated esters, e. g.,

- (a) Esters of unsaturated acids (e. g. those listed under (5) above as well as unsaturated aromatic acids such as cinnamic and coumaric) with mono- and poly-hydric alcohols, or other hydroxy compounds (including phenols). Examples of such alcohols and hydroxy compounds are:

- Methyl alcohol
 Ethyl alcohol
 Propyl alcohols
 Butyl alcohols
 Amyl alcohols
 Lauryl alcohols
 Cetyl alcohols
 Cyclohexanol
 Alkylated cyclohexanols, e. g.,
 Methyl cyclohexanol
 Amyl cyclohexanol

- Benzyl alcohol
 Furfuryl alcohol
 Tetrahydrofurfuryl alcohol
 Ethylene glycol
 Propylene glycol
 Di-ethylene glycol
 Glycerol
 Glyceritol
 Phenol
 Polyhydroxy-benzenes
 Alkylated phenols
 Naphthols
 Unsaturated alcohols (e. g. those listed under (1) above).

- (b) Esters of unsaturated alcohols (e. g. those listed under (1) above) with organic acids, either aliphatic or aromatic, or with inorganic acids. Examples of such acids are:

- Aliphatic acids, including
 Saturated acids, such as:
 Acetic acid
 Propionic acids
 Butyric acids
 Lauric acids
 Palmitic acid
 Stearic acid
 Oxalic acid
 Citric acid
 Lactic acid
 Glycolic acid
 Malonic acid

- Unsaturated acids, such as those listed under (5) above.

- Aromatic acids, including:
 Benzoic acid
 Phthalic acids
 Salicylic acid
 Anthranilic acid
 Cinnamic acid

- Cyclo-aliphatic acids, including:
 Naphthenic acids
 Hexahydrobenzoic acid

- Heterocyclic acids including:
 Furoic acid
 Pyrrol carboxylic acids
 Pyridine carboxylic acids

- Inorganic acids, including:

- Hydro-halogen acids
 Oxy-halogen acids
 Sulphurous acid
 Sulphuric acid
 Thiosulphuric acid
 Carbonic acid
 Thiocarbonic acids
 Hydrogen sulphide
 Phosphorous acid
 Thiophosphorous acids
 Phosphoric acid
 Thiophosphoric acids
 Cyanic acid
 Thiocyanic acid
 Hydrocyanic acid
 Boric acid

- (8) Salts of unsaturated acids, including the
 Ammonium and substituted ammonium
 Sodium
 Calcium
 Barium
 Cobalt
 Aluminum
 Magnesium
 Zinc
 Lead

Salts of unsaturated acids generally, and more specifically of such acids as those listed under (5) above and of unsaturated aromatic acids.

In addition to the compounds listed above, commercial products comprising complex mixtures of unsaturated oxygen-bearing organic compounds may be used as the "unsaturated" reactant. Examples of such materials are the fatty oils of unsaturated character, e. g.,

- Castor oil
 China-wood oil
 Corn oil
 Cottonseed oil
 Croton oil
 Lard oil
 Linseed oil
 Menhaden fish oil
 Rape seed oil
 Soya bean oil
 Sperm oil

Additional material, for use as the "unsaturated" reactant in the condensation, may be derived from any of the above fatty oils are, e. g.,

- (1) Acids, extracted from the oils by direct hydrolysis, or by saponification and subsequent hydrolysis, or otherwise.
 (2) Esters, produced by esterifying the acids of (1) e. g. to form esters analogous to any of those listed under (7) in Table No. 2.
 (3) Soaps, produced by saponifying the oils directly or by neutralizing the acids of (1) with alkalies, e. g. to form salts analogous to those listed under (8) in Table No. 2.

The unsaturated oxygen compounds are of particular importance and may, therefore, be classified in further detail according to the nature of the attachment of the oxygen atom to the molecule, viz:

Table No. 3

- I'. Directly attached to one or more carbon atoms, as in the case of:
 (1') Ethers and analogous compounds.
 (2') Compounds containing the

- radicle, such as alcohols and other derivatives of carbol (including phenols, cresols, naphthols, etc.).
 (3') Compounds containing the carbonyl $>\text{C}=\text{O}$ radicle, such as amides, aldehydes, ketones, organic acids, esters and salts of organic acids (including such salts of both inorganic and organic bases), thio-acids and esters and salts of thio-acids.
 (4') Compounds in which oxygen forms a part of a ring structure, e. g. compounds containing the furyl or hydro-furyl groups.
 (5') Compounds with an inorganic radicle where the oxygen is directly attached to a carbon atom, e. g.,

- Arsenites
 Hypochlorites
 Phosphites
 Thiophosphates
 Thiophosphites
 β -hydroxylamines
 Borates

- II'. Indirectly attached through the means of some other atom, e. g., in the form of an inorganic radicle, e. g.,

- Arsonate
 Chlorate
 Chlorite
 Cyanate
 α -Hydroxylamine
 Nitrate
 Nitrite
 Nitro
 Nitroso
 Oxime
 Perchlorate
 Phosphate
 Sulphate
 Sulphite
 Sulphinic acid
 Sulphone
 Sulphonic acid
 Sulphoxide
 Thiophosphate
 Thiophosphite
 Thio-sulphate

(Note: This class includes salts of organic bases with inorganic oxy-acids.)

In addition to the unsaturated compounds above described, certain unsaturated cyclic compounds are also of use, such as the cyclo-olefines (e. g. cyclo-hexene) and derivatives of them. Examples of such unsaturated cyclic compounds are:

- Hydrocarbons:
 Cyclobutene
 Methyl cyclobutene
 Methylenecyclobutane
 Cyclopentene
 Methyl cyclopentenes
 Lauriene
 Cyclopentadiene
 Fulvenes
 Di-cyclopentadiene
 Cyclohexene
 Methyl cyclohexenes
 Cyclohexadienes
 Methyl cyclohexadienes
 p-Menthenes
 p-Menthadienes
 Terpenes
 Limonene
 Di-cyclohexadiene
 Dihydronaphthalene
 Dihydronaphthalene
 Tetrahydronaphthalene
 Pinene
 Camphene

Oxygen-containing compounds:
 Alcohols

- Terpineol
 Isopulegol
 Dihydrocarveol
 Pinocarveol

Aldehydes

- Ketones
 Pulegone
 Piperitone
 Carvone
 Eucarvone
 Ionone
 Pinocarvone
 Verbenone
 Carvenone

Ethers

- Pinol
 Tetrahydro-anisole
 Tetrahydro-phenetole

Acids

- Laurolenic acid
 Chaumoogric acid
 Hydnoearpic acid
 Tetrahydrobenzoic acid
 Tetrahydronaphthalic acid
 Dihydrophthalic acids
 Tetrahydrotoluic acids
 Tetrahydro-xrylic acids
 Methyl cyclohexylidene acetic acid
 Fural acrylic acid
 Fural malonic acid
 Benzal malonic acid
 Benzal propionic acid
 Benzal lactic acid
 Abietic acid

- 50 Commercial products comprising complex mixtures of unsaturated cyclic organic compounds may also be used, e. g.,

- 55 Turpentine
 Pine oil

ORGANIC RING COMPOUNDS

The organic ring compounds may be classified as follows:

Table No. 4

A. "Carbon ring" type compounds—

- (a) Of the aromatic (i. e. benzenoid) or allied type, including benzene, naphthalene, anthracene, and their derivatives; also compounds of the bridged ring type, such as the terpenes, and related compounds.
 (b) Of the class including the cycloparaffins, cyclo-olefines, etc. Examples of this class are the following:
 (1) Hydrogenation products of benzene, (e. g. cyclohexane, cyclohexene, cyclohexadiene).
 (2) Hydrogenation products of naphthalene, (e. g. decahydronaphthalene, tetrahydronaphthalene, etc.).
 (3) Naphthenes, naphthemic acid, etc.
 (c) Of the mixed type such as hydrindene, hydranthracene, etc.
 B. "Heterogeneous ring" type compounds (i. e. heterocyclic)—
 (a) Of the aromatic (benzenoid) or allied type including pyridine, quinoline, etc., and their derivatives.
 (b) Other types such as furan, thiophene, pyrrole, etc., and their derivatives.

The organic ring compounds which are preferred for my purpose are those of the aromatic type (A (a) and B (a) of the table above). These may be further classified as follows:

Table No. 5

I. Hydrocarbons—

- (A) Benzene and its homologs such as toluene, xylene, cymene, ethyl-benzene, mesitylene.
- (B) Polynaphthalenes such as diphenyl, diphenyl benzene, and homologs of them such as o-phenyl toluene, poly-ethyl diphenyls, propyl diphenyl.
- (C) Condensed ring hydrocarbons
  - (1) Naphthalene and its homologs, such as the methyl naphthalenes, ethyl naphthalenes, propyl naphthalenes.
  - (2) Phenanthrene and anthracene and their homologs such as the mono- and di-methyl, and propyl and iso-propyl, substitution products, e. g. retene.
  - (3) Chrysene and picene and their homologs.
- (D) Compounds resulting from substitution of aryl groups in compounds of classes (A), (B) and (C), e. g., di-benzyl, di-naphthyl, phenyl naphthalene, the polyphenylmethanes, etc.
- (E) Bridged ring hydrocarbons such as certain of the terpenes and related compounds including pinene, camphene and limonene.

II. Heterocyclic compounds of the aromatic or allied type such as pyridine, quinoline, thiophene, etc., and their derivatives.

III. Substitution products (other than hydrocarbon homologs) of compounds of classes I and II, including:

- (A) Oxygen-bearing substitution products. (See Table No. 6 below, for further classification.)
- (B) Halogen-bearing substitution products.
- (C) Other substitution products, such as those resulting from substitution of the following groups:
  - Amino, and substituted amino groups
  - Imino
  - Azo
  - Hydrazo
  - Hydrazine
  - Nitrile
  - Isonitrile
  - Mercapto
  - Sulphide
  - Polysulphide
  - Thiocyanate
  - Iothiocyanate
  - Dithiocarboxylic acids (also ester and salt groups derived therefrom)

IV. Derivatives of the compounds included in Classes I, II, and III resulting from addition reactions, such as hydrogenation, halogenation, etc. Examples of such compounds are the hydro-naphthalenes, phenyl cyclohexane, phenyl cyclohexanol, cyclohexyl phenol, naphthalene tetrachloride.

Attention is called to the fact that certain of the compounds may belong to more than one class; as, for example, the halogenated phenols which belong in Class III (A) and III (B), or the halogenated amino phenols, Class III (A), (B) and (C).

The oxygen-bearing aromatic compounds (Class III (A) of Table No. 5) are of particular importance, and are, therefore, classified in further detail according to the nature of the attachment of the oxygen to the molecule, viz:

Table No. 6

I'. Directly attached to one or more carbon atoms, as in the case of:

- (1') Ethers and analogous compounds.
- (2') Compounds containing the

- radicle, such as alcohols and other derivatives of carbinal (including phenols, cresols, naphthols, etc.)
- (3') Compounds containing the carbonyl $>\text{C}=\text{O}$ radicle, such as amides, aldehydes, ketones, organic acids, esters and salts of organic acids (including such salts of both inorganic and organic bases), thio-acids and esters and salts of thio-acids.
- (4') Compounds in which oxygen forms a part of the ring structure, e. g. furan and its derivatives, etc.
- (5') Compounds with an inorganic radicle where the oxygen is directly attached to a carbon atom, e. g.,
  - Arsenites
  - Hypochlorites
  - Phosphites
  - Thiophosphates
  - Thiophosphites
  - β -Hydroxylamines
  - Borates

II'. Indirectly attached through the means of some other atom, i. e., in the form of an inorganic radicle, e. g.,

- Arsenate
- Chlorate
- Chlorite
- Cyanate
- α -Hydroxylamine
- Nitrate
- Nitrite
- Nitro
- Nitroso
- Oxime
- Perchlorate
- Phosphate
- Sulphate
- Sulphite
- Sulphinate acid
- Sulphone
- Sulphonic acid
- Sulphoxide
- Thiophosphate
- Thiophosphite
- Thiosulphate

(NOTE: This class includes salts of organic bases with inorganic oxy-acids.)

For specific examples of oxygen-bearing aromatic compounds, reference may be had to the table beginning on page 6 of my co-pending application Ser. No. 737,070, filed July 26, 1934. These examples include both the unhalogenated compounds listed and the halogenation products of them.

The classification of the unsaturated compounds and of the organic ring compounds is sufficiently broad so that the two classes of compounds overlap. There are certain compounds belonging to both classes, as indicated by this overlapping, which are suitable for either use; for example, an aromatic compound containing a double-bonded pair of carbon atoms in a side chain may be used either as the unsaturated compound or as the organic ring compound in carrying out the reaction in the presence of aluminum chloride. Examples of such compounds are:

Table No. 7

- Stilbene
- Styrene
- Chlor styrenes
- Vinyl phenols
- Cinnamic alcohol
- Cinnamic aldehyde
- Vinyl anisoles
- Allyl phenyl ether
- Allyl phenols
- Aromatic esters of unsaturated acids, e. g.,
  - Benzyl acrylate
  - Benzyl oleate
  - Phenyl oleate
- Esters of unsaturated alcohols with aromatic acids, e. g.,
  - Allyl benzoate
  - Oleyl benzoate
  - Allyl salicylate
- Unsaturated aromatic acids, e. g.,
  - Coumaric acid
  - Cinnamic acid
- Esters of unsaturated aromatic acids (including coumaric and cinnamic acids), e. g.,
  - Methyl cinnamate
  - Lauryl cinnamate
  - Benzyl cinnamate
  - Allyl cinnamate
  - Oleyl cinnamate
- Salts of unsaturated aromatic acids (including coumaric and cinnamic acids) with:
  - (a) Inorganic bases, e. g., to form salts of:
    - Ammonium
    - Sodium
    - Calcium
    - Aluminum
    - Magnesium
    - Zinc
    - Lead
  - (b) Organic bases, e. g.,
    - Ethyl amines
    - Ethanol amines, such as tri ethanol amine
    - Aromatic amines, such as aniline

The following table gives typical examples of the unsaturated compounds and of the organic ring compounds which are suitable for use in carrying out the above reaction in the production of compounds suitable for use in the field of lubrication in accordance with this invention.

11
Table No. 8

Typical unsaturated compounds	Typical organic ring compounds
Ethylene	Benzene
Propylene	Toluene
Isopropylene	Xylenes
n-Butylene	Ethylenes
Isobutylene	Naphthalene
Polymerized butylenes	Methyl naphthalenes
Polymerized pentenes	Ethyl naphthalenes
Polymerized hexenes	Anthracene
Cracked gasoline	Retene
Cracked kerosene	Diphenyl
Cracked waxes	Benzophenone
Cracked heavy oils	Anthraquinone
Cracked petroleum	Diphenyl ether
Allyl alcohol	Salicylic acid
Oleyl alcohol	Triphenyl phosphate
Acrolein	Triphenyl phosphite
Acrylic acid	Tricresyl phosphate
Crotonic acid	Phenyl cyclohexane
Linoleic acid	hydro-naphthalenes
Ricinoleic acid	Chlor-naphthalenes
Butyl ricinoleate	Chlor-benzenes
Methyl ricinoleate	Chlor-diphenyls
Lauryl ricinoleate	Chlor-diphenyl ethers
Methyl oleate	Chlor-benzophenones
Benzyl oleate	Benzonitrile
Oleyl stearate	Methyl salicylate
Oleyl acetate	Methyl chlorosalicylates
Allyl stearate	
Allyl oleate	Retene oil
Oleyl oleate	Tar acids.
Aniline oleate	
Triethanolamine oleate	
Calcium oleate	
Aluminum oleate	
Calcium ricinoleate	
Calcium linoleate	
Calcium stearolate	
Methyl linoleate	
Methyl stearolate	
Lauryl propiolate	
Methyl cinnamate	
Allylene oxide	
Allylin	
Tetrachlorethylene	
Allylamine	
Allyl amine acetate	
Allyl mercaptan	
Allyl cyanide	
Allyl thiocyanate	
Allyl trisulfide	
Chlorbenzylestes	
Chloracetylenes	
Chlor acrylic acids	
Chlor crotonic acids	
Chlor oleic acids	
Tri-allyl phosphate	
Tri-allyl phosphite	
Castor oil	
Rape seed oil	

The products resulting from the reaction of unsaturated compounds with oxygen-bearing organic ring compounds are, for certain purposes, superior to corresponding oxygen-free compounds, probably as a result of the tendency of oxygen-bearing compounds to be strongly adsorbed on metal surfaces. It is to be noted that the products of reaction of oxygen-bearing unsaturated compounds with aromatic compounds are to be preferred for the same reasons.

Included among the examples of such preferred compounds are the condensation products resulting from condensation of metallic salts of unsaturated fatty acids with aromatic compounds. Such condensation products are the salts of aromatic substituted fatty acids. Specific examples of these are the condensation products resulting from the condensation of aluminum oleate with the aromatic compounds listed above under "Typical organic ring compounds." Examples of such condensation products are the following:

Aluminum salts of
Phenyl stearic acid
Tolyl stearic acid
Xylyl stearic acid
Naphthyl stearic acid
Xenyl stearic acid
Phenoxy phenyl stearic acid
Chlorophenyl stearic acid

The products resulting from the reaction of unsaturated compounds with halogen-bearing organic ring compounds constitute a class which are very effective in thin film lubrication, because of their ability to prevent seizing or scoring of bearing surfaces subjected to extreme pressures. Such compounds are most effective when oxygen is also present in the molecule; as, for example, the products resulting from the reaction of unsaturated compounds such as cracked kerosene with halogenated oxygen-bearing aromatic compounds such as chlorinated diphenyl ether, or the chlor aryl phosphates, e. g. the tri-chlor-phenyl phosphates.

15 In addition to the halogen-bearing compounds, organic derivatives of any of the inorganic oxy-acids are also suitable in producing products useful in extreme pressure lubrication. Such products may be formed by the reaction either of unsaturated aliphatic derivatives of such acids (e. g. allyl esters of sulphuric and phosphoric acids) with organic ring compounds, or of aryl derivatives of such acids (e. g. triphenyl and tricresyl phosphate) with unsaturated compounds or by treating a suitable condensation product with a suitable reagent.

In making use of halogen-bearing compounds, for some purposes, it is desirable that the halogen be attached to a carbon atom which is part of 30 a benzenoid ring structure to prevent the corrosive effect resulting from the easier hydrolysis of other halogen compounds to form hydro-halogen acids. However, where very extreme pressures are encountered, it may be necessary to employ 35 more chemically active materials. In the latter case, the halogen addition products of aromatic compounds are particularly useful, because the degree of reactivity of the combined halogen may be easily controlled.

40 It may be noted that halogen-bearing products may also be obtained by first reacting the unsaturated compound with the ring compound, and then halogenating. This is usually the preferred method of preparing halogen-bearing 45 products except when it is desired to have the halogen attached to a benzenoid structure. It will be noted that the above referred to halogen-bearing compounds are of the type which contain a substantial amount of halogen.

Besides the halogen derivatives, other derivatives contemplated hereby for use in lubrication may also be formed from the products of the condensation reaction (as well as from methylated 55 organic ring compounds); for example, by esterification or saponification when the material is a hydroxy compound (e. g. an alcohol, phenol, or acid) or a base (e. g. a substituted ammonia), or by treatment with organic or inorganic reagents (e. g. PCl_3 , $POCl_3$, $PSCl_3$, P_2S_5 , BCl_3 , S_2Cl_2 , $SOCl_2$, Grignard reagents, etc.) when the organic material is of suitable type (e. g. hydroxyl-containing).

An important group of compounds contemplated 65 by this invention for use in the field of lubrication are methyl derivatives of organic ring compounds containing an element in addition to carbon and hydrogen. This group includes methyl derivatives of the organic ring compounds referred to above, which derivatives also contain an element in addition to carbon and hydrogen and includes, as well, the methyl derivatives of the condensation products referred to above. Examples of this group of compounds are as follows:

Chlor-toluenes
Chlor-xlenes
Chlorinated mono- and poly-methyl diphenyls
Chlorinated mono- and poly-methyl naphthalenes
Mono- and poly-methyl diphenyl ethers
Mono- and poly-methyl benzophenones
Mono- and poly-methyl acetophenones
Mono- and poly-methyl diphenylene oxides
Mono- and poly-methyl dinaphthyl ketones
Mono- and poly-methyl dinaphthyl ethers
Mono- and poly-methyl dixenyl ethers
Mono- and poly-methyl anthraquinones
Mono- and poly-methyl benzonitriles
Xylyl sulphides and polysulphides and halogen-bearing or other derivatives of the above, e. g.,
Methyl chlor-benzophenone
Chlor-xylyl sulphides and polysulphides

Additional specific examples of the addition agents of my present invention as found in my said parent application, Serial No. 737,070, are the halogen derivatives, and more specifically the chlorine-containing derivatives of the following compounds:

Aluminum phenyl mercapto stearate
Aluminum phenyl stearate
Calcium phenyl mercapto stearate
Calcium phenyl stearate
Zinc phenyl stearate
Sodium benzoate
Sodium thiobenzoate
Zinc benzoate

Additional specific examples disclosed in this parent application are the alkylated derivatives of the above compounds, including specifically the halogen derivatives, and more particularly the chlorine derivatives, of the following:

Alkylated sodium benzoate
Alkylated sodium thiobenzoate
Alkylated zinc benzoate

In my aforesaid parent application, Serial No. 760,038 will be found listed as specific examples of addition agents of the present invention the condensation products of aluminum oleate with aromatic compounds, and specifically with naphthalene, anthracene, toluene, xylene, diphenyl, and phenanthrene, yielding for example the following compounds:

Aluminum naphthyl stearate
Aluminum anthracyl stearate
Aluminum tolyl stearate
Aluminum xylyl stearate
Aluminum xenyl stearate
Aluminum phenanthryl stearate

All of the above identified specific examples of the addition agents of this invention are compounds which contain:

- An aromatic nucleus;
- An aliphatic substituent; and
- An inorganic substituent.

It will be noted that the inorganic substituent in some cases is attached to the aliphatic substituent, as in the case of the salts of the aro-

matic substituted fatty acids, specifically aluminum phenyl stearate, and in other cases is attached to the aromatic nucleus as in the case of those examples which contain the chlor phenyl group, for example, the condensation product of chlorbenzene with aluminum oleate; the principal product of such condensation being the aluminum salt of chlor phenyl stearic acid.

It should be noted that the last named example 10 contains a plurality of inorganic substituents, one of which is attached directly to the aromatic nucleus, and the other is attached to the aliphatic substituent.

In the foregoing identification of the various 15 classes of addition agents useful in my present invention occur two classes of compounds respectively characterized by the presence of the radicle $-\text{O}-\text{M}$, where M is a metal, and the radicle $-\text{S}-\text{M}$, where M is a metal. These two classes 20 of compounds may be generically defined as compounds containing the radicle $-\text{X}-\text{M}$, where X is either oxygen or sulphur, and M is a metal.

It will be noted that these radicles may be attached at various points in the molecule and 25 need not be attached exclusively to a hydrocarbon group; as in the mercaptides (previously identified as examples of sulphur-containing addition agents) but may as well be attached to a radicle which contains other substituents. For example, the $-\text{X}-\text{M}$ radicle may be attached to a

30 radicle, where X' is oxygen or sulphur, as in the form of the

35 40 radicle.

The radicle comprising the $-\text{X}-\text{M}$ group may be attached either directly to the aromatic nucleus, as in the case of alkylated zinc benzoate

50 55 or the radicle comprising the $-\text{X}-\text{M}$ group may be a part of the aliphatic radicle, as in the case of the salts of aromatic substituted fatty acids, as for example, aluminum phenyl stearate.

The broad class of substituted organic ring compounds containing an element in addition to carbon and hydrogen and an aliphatic substituent constituting the materials useful as and in lubricants in accordance with my invention of which several different types of examples and methods of preparing the same have been given above, 65 when used as addition agents in lubricating compositions and lubricating compositions containing the same, will be found to have the following uses and advantages:

In addition to the advantages obtained by the 70 use of certain products contemplated by this in-

vention to increase the film strength of lubricating oils or as lubricants possessing high film strength, other advantages may be obtained as follows:

Certain of the compounds contemplated herein are extremely stable and therefore, resistant to decomposition, oxidation and gum-forming or sludge-forming reactions, especially when used in crankcase lubricants in internal combustion engines. In general, the class of products which contain long-chain structures and/or multiple chain structures, when present in liquids, reduce the rate of change of viscosity with the temperature and usually have a tendency to prevent precipitation of crystalline or gelatinous materials, such as waxes, on chilling. Lubricants comprising certain of such long and/or multiple chain products, therefore, have the advantages of improved viscosity index or lowered pour point.

It has been found that certain of the compounds above described, either alone or in combination with lubricating oils and/or other materials, such as organic oxygen compounds and organic halogen compounds, are capable of reducing the rate of wear of bearing surfaces, particularly during thin-film lubrication and especially when one of the bearing surfaces is of a so-called bearing-metal type such as brass, bronze, babbitt, lead-bronze, cadmium-silver, cadmium-nickel alloys, etc., these being generally classified as bearing metals containing a characterizing amount of lead, tin, copper, zinc, silver, nickel, cadmium, aluminum or tellurium. This effect may, in some cases, be independent of the property also possessed by some of such materials for reducing friction, that is, reducing power losses in bearings.

Certain compounds which are particularly suitable for increasing the film strength of lubricating oils, when added in small amounts, for example, highly chlorinated naphthalene, have the disadvantage of being relatively insoluble in mineral oils, particularly at low temperatures. The oil solubility of these materials may be increased by alkylating, or adding an aliphatic substituent generally, for example, reacting them with unsaturated compounds, as disclosed herein, as for example, in reacting hexachlor naphthalene with ethylene to produce polyethyl chlor-naphthalenes which are completely miscible with mineral lubricating oils.

It will be observed that the class of materials contemplated for use as addition agents to lubricants in accordance with this invention has a relatively broad range as to stability and also as to chemical reactivity.

With regard to stability, the addition agent for a particular use should be selected from those sufficiently stable not to be too quickly destroyed under operating conditions. For example, the thermal stability of an addition agent to be used in a crankcase lubricant should be relatively high so that the addition agent will not be too readily decomposed by contact with the heated metal surfaces to which the lubricant is exposed. Those materials which may be distilled without substantial decomposition, either at atmospheric pressure or under vacuum, at temperatures above 140° C. are often of advantage for such uses. Where the lubricant is intended for very high temperature applications, as for example, in the crankcases of Diesel engines and aviation engines, the materials may advantageously be capable of such distillation at temperatures above 170° or even 200° C.

As to the re-activity of the addition agent and particularly with regard to its corrosive action, the addition agent should be selected for a particular use so that it will not react so readily with the metal surfaces with which it comes in contact as to damage them in normal use. However, when used in conjunction with a corrosion-inhibiting agent, e. g. in accordance with the teachings of my co-pending application Ser. No. 119,132, filed January 5, 1937, relatively highly reactive materials such as those which would normally be corrosive may be used to advantage, particularly where high film strength of the compounded lubricant is of special importance.

Since the addition of certain materials of the class including the above enumerated, which themselves are relatively non-viscous, will reduce the viscosity of the oil base to which the same are added, if a large percentage of such compounds is added, there will be a tendency to destroy "thick-film" lubrication because of the reduction in viscosity of the composition. If an excessive quantity of such compounds is added, all of the lubrication will then be of the "thin-film" type and, therefore, produce a decided increase in the total amount of friction developed. In such cases, it is advisable to employ the material as an addition agent in amounts less than about 20%.

As previously indicated, the materials contemplated for use in accordance with my invention are often useful as lubricants themselves; however, due to their relatively high cost, generally satisfactory results may be secured by incorporating minor amounts of such materials with other lubricants such as mineral lubricating oil. The particular properties of the lubricant desired will generally dictate the particular material selected for addition to the oil and the percentage in which the same is employed. In general, when preparing a lubricating composition for ordinary lubricating purposes, such as the lubrication of automobiles, i. e., crankcases and gear boxes, the concentration of the addition agent need not be greatly in excess of 20% in a refined mineral lubricating oil in order to provide an entirely satisfactory lubricant. In general, it will be found that percentages much less than 20% will be entirely satisfactory, i. e., in general, percentages necessary for the desired results will lie below 10%.

When compounding a lubricant to be used as a crankcase lubricant, it will usually be found that percentages ranging from .10% to about 2%, or 5%, will be entirely adequate for the purpose. The particular percentage range within which a certain material is added will, as above indicated, also depend upon the characteristics of such material, such as its activity and its tendency to react either chemically or physico-chemically with the bearing surfaces in order to provide the proper thin-film lubrication.

The foregoing discussion with respect to the percentages of the materials enumerated above which may be used in lubricating oil bases, such as mineral oil, have been given in connection with the preparation of a lubricant which is particularly characterized either by high film strength, low coefficient of friction (oiliness) and the like. Many of the compounds contemplated for use by my invention may be employed to otherwise improve the properties of mineral oil, such as by improving the cold test, reducing the tendency of the oil to develop sludges, inhibiting oxidation, or stabilizing the oil against the formation of acids during standing or in use, inhibiting cor-

rosion, or in dissolving gummy and like deposits which occur when the lubricant containing the same is admitted to regions of high temperature such as in or adjacent to the combustion chamber. Such use is efficacious in overcoming ring-sticking tendencies in internal combustion engines. When the addition agents are added for this latter purpose, low percentages, usually much below those previously given, will be sufficient. Percentages of from 1.0% or .1% to as low as .001% or less of certain of the compounds will be found to be sufficient for particular purposes.

It will be observed that materials included within the contemplation of my invention as lubricants or addition agents to lubricants are generally possessed of extremely low volatility, even at elevated temperatures and certain of the compounds are characterized by the fact that they are stable and non-volatile even at extremely high temperatures which renders them particularly suitable for use as or in lubricants operating under conditions of high temperature; for example, Diesel engines and aviation engines.

When used in conjunction with a mineral lubricating oil, it is obvious that generally only such amounts of the addition agent may be included as are soluble in the specified amount of oil. By the term "soluble," as herein used, it is intended to indicate the ability to form not only true solutions but also any form of substantially permanently homogeneous composition when incorporated in mineral oil. With most of the compounds there is usually little difficulty, especially if the incorporation is effected in the manner described in Cornell Patent No. 2,042,880, and since quite small percentages often give remarkably improved results it is seldom of extreme importance that the addition agents be oil-soluble in all proportions. Also, certain compounds are of value as gelling or bodying agents when used in amounts greater than are strictly soluble.

When the materials included within the contemplation of my invention, as above defined, are used as or in lubricants in the manner hereinbefore specified, it will be understood that other agents may be employed in conjunction therewith, so long as such other agents are not incompatible with the materials comprising my invention. Thus, for example, other agents designed to supplement the characteristics of the materials herein identified in providing a lubricant having any of the previously named desirable characteristics may be employed, as well as agents which supply any of such characteristics which are not provided by the particular materials used in practicing my invention.

The materials above identified, contemplated for use in practicing my invention have been particularly referred to as useful as or in lubricants. It will be observed that they may likewise be employed to advantage as addition agents in fuels employed in internal combustion engines, either in their pure state or admixed with other fuel addition agents or included as a constituent in a lubricant added to the fuel. Certain of these materials are, as previously indicated, particularly suitable for use in fuels on account of their ability to withstand high temperatures.

While the lubricating compositions which have been described herein as illustrating one embodiment of the invention have been generally referred to as "oils," i. e., liquids, this invention is, however, also applicable to the solid and semi-solid types of lubricants commonly referred to in the trade as greases, bodied oils, etc. In this

connection, it should be noted that certain of the addition agents contemplated for use herein may be employed for the additional purpose of bodying or thickening the lubricant to which they are added.

Throughout the foregoing description, certain substances have been generically referred to as "halogenated" or "halogen-bearing." In general, the "chlorinated" or "chlorine-bearing" species will be found preferable on account of the lower cost and generally satisfactory effectiveness of chlorine as compared with the other halogens. The "fluorinated" or "fluorine-bearing" species of certain of the named materials will be found especially useful on account of the inherently greater stability of certain of the fluorine compounds, as compared with the other halogens.

It will also be found that two or more halogens such as, for example, chlorine and bromine or chlorine and fluorine, may be employed together in the same molecule in a "halogenated" or "halogen-bearing" substance where the same is thus identified in the foregoing description.

Included in the foregoing description of this invention, reference has been made to the use of the condensation products resulting from the reaction between certain-named constituents. It will be observed that the constituents themselves which have been previously referred to as useful in the preparation of the condensation product are, in some cases, useful as addition agents in lubricating compositions. It is therefore to be understood that this invention contemplates the production of lubricating compositions, the properties of which affecting its use as a lubricant have been improved by incorporating therein a minor amount of any of the named constituents which have been previously referred to as constituents useful as reactants to form the condensation products. In certain cases, these constituents, as such, may be added separately to the lubricating composition or may be included therein by virtue of their inclusion in the reaction product, i. e., if the condensation reaction is not carried to completion and the condensation product purified by removal of the unreacted constituents.

The foregoing is to be understood as referring not necessarily to the combined presence of the two types of unreacted constituents in the composition but is to include also the use as the sole addition agent in a lubricating composition of any of the named constituents of both classes.

In the foregoing description of this invention, general reference has been made to lubricating compositions including certain particularly identified materials. It will be understood that in general the compositions resulting from the present invention will generally, on account of cost of materials used, consist largely of lubricating oils such as, for example, mineral oils, animal oils and vegetable oils. A mixture of two or more of such oils along with the named addition agents will be found highly useful for certain purposes. As a specific example, a mixture of a mineral oil, a fatty oil such as lard oil, and an addition agent selected from those described will be found to possess improved properties for certain purposes with respect to oiliness by virtue of the presence therein of the fatty oil.

The oil base

The oil base of my lubricating compositions is a lubricating oil of the type best suited for the particular use for which the ultimate composition

is designed. When the lubricating compositions of my invention are designed for the lubrication of automobiles, the oil base will of course preferably consist of a refined mineral lubricating oil of lubricating viscosity for the particular point of application. In other words, the conventional gear oil may be used for the lubrication of gears, for example, mineral oil having a viscosity range of from an S. A. E. 80 to an S. A. E. 140. Generally a lighter, more highly refined oil may be used in the crank case, such as a motor oil having a viscosity range of from an S. A. E. 10 to an S. A. E. 50.

This invention is applicable to lubricating compositions in which the base may consist either entirely or in part of synthetic oils, hydrogenated oils, and volatilized oils.

The oil base may also desirably contain other well known constituents such as those which improve the oiliness, pour point, cold test, and oxidation properties, etc., of the oil. In general, compositions of my invention may be employed with any commercially available addition agents for the above defined purposes since they are generally compatible with the same in the amounts usually used.

In the foregoing references to mineral oil is meant to be included oils refined from any of the various crude oils, for example, those obtained from the Pennsylvania, Mid-Continent, and Gulf Coastal fields, and oils refined by any of the usual refining processes including distillation, solvent extraction, acid treatment, clay treatment, dewaxing, etc.

The viscosity of the base oil chosen should be such that the final composition will have viscosity suitable for the particular use for which it is intended. The viscosity of the final composition may, in certain cases, be advantageously less than that which would be selected in the case of the use of a base oil alone. These viscosities may range from those of spindle oils or lighter through the range usually selected for crankcase lubricants, to those of heavy gear oils, cylinder oils, and the like, or even heavier.

Many of the addition agents contemplated by this invention are particularly suitable for use with mineral oils containing sufficient quantities of wax or wax-like constituents to cause them, without the use of an addition agent, to cease to flow at low temperatures.

Other modes of applying the principle of the invention may be employed, change being made as regards the details described, provided the features stated in any of the following claims or the equivalent of such be employed.

I therefore particularly point out and distinctly claim as my invention:

1. An extreme pressure lubricant comprising a major proportion of mineral lubricating oil and an aromatic compound containing (a) an aromatic nucleus, (b) an aliphatic substituent containing more than three carbon atoms, and (c) an inorganic substituent containing an element of the class consisting of oxygen and sulphur, said compound present in an amount sufficient to increase the load carrying capacity of the composition so as to prevent seizure and scoring of the bearing lubricant thereby when operated under conditions of boundary lubrication.

2. An extreme pressure lubricant comprising a major proportion of mineral lubricating oil and an aromatic compound containing (a) an aromatic nucleus, (b) an aliphatic substituent containing more than ten carbon atoms, and (c)

an inorganic substituent containing an element of the class consisting of oxygen and sulphur, said compound present in an amount sufficient to increase the load carrying capacity of the composition so as to prevent seizure and scoring of the bearing lubricant thereby when operated under conditions of boundary lubrication.

3. An extreme pressure lubricant comprising a major proportion of mineral lubricating oil and an aromatic compound containing both an aliphatic substituent and a sulphur bearing inorganic substituent, said compound present in an amount sufficient to increase the load carrying capacity of the composition so as to prevent seizure and scoring of the bearing lubricant thereby when operated under conditions of boundary lubrication.

4. An extreme pressure lubricant comprising a major proportion of mineral lubricating oil and an aromatic compound containing both an aliphatic substituent having at least three carbon atoms and an oxygen bearing inorganic substituent, said compound present in an amount sufficient to increase the load carrying capacity of the composition so as to prevent seizure and scoring of the bearing lubricant thereby when operated under conditions of boundary lubrication.

5. An extreme pressure lubricant comprising a major proportion of mineral lubricating oil and an aromatic compound containing both an aliphatic substituent having at least three carbon atoms and a sulphur bearing inorganic substituent, said compound present in an amount sufficient to increase the load carrying capacity of the composition so as to prevent seizure and scoring of the bearing lubricant thereby when operated under conditions of boundary lubrication.

6. A lubricating composition comprising an aromatic compound containing (a) an aromatic nucleus, (b) an aliphatic substituent, and (c) the radicle —X—M where X is of the class consisting of oxygen and sulphur and M is aluminum.

7. A lubricating composition comprising an aromatic compound containing (a) an aromatic nucleus, (b) an aliphatic substituent, and (c) the radicle —X—M where X is of the class consisting of oxygen and sulphur and M is a metal selected from the class consisting of cobalt and nickel.

8. An extreme pressure lubricant comprising a major proportion of mineral lubricating oil and a halogen bearing aromatic compound containing both an aliphatic substituent and an inorganic substituent containing an element of the class consisting of oxygen and sulphur, said compound present in an amount sufficient to increase the load carrying capacity of the composition so as to prevent seizure and scoring of the bearing lubricant thereby when operated under conditions of boundary lubrication.

9. A lubricating composition comprising a major proportion of mineral lubricating oil and from .001% to 20% of an aromatic compound containing (a) an aromatic nucleus, (b) an aliphatic substituent having at least 3 carbon atoms, and (c) an inorganic substituent containing the radical —O—M where O is oxygen and M is a metal.

10. A lubricating composition comprising a major proportion of mineral lubricating oil and from .001% to 20% of an aromatic compound containing (a) an aromatic nucleus, (b) an aliphatic substituent having at least 3 carbon atoms, and (c) an inorganic substituent containing the rad-

ical —S—M where S is sulphur and M is a metal.
